UNITED STATES PATENT OFFICE.

ALBERT KORTUM, OF BROOKLYN, NEW YORK, ASSIGNOR TO THE ZUCKER & LEVETT & LOEB COMPANY, OF NEW YORK, N. Y.

POLISHING-WHEEL.

SPECIFICATION forming part of Letters Patent No. 605,641, dated June 14, 1898.

Application filed December 21, 1897. Serial No. 662,846. (No model.)

To all whom it may concern:

Be it known that I, ALBERT KORTUM, a citizen of the United States, residing at Brooklyn, in the county of Kings, State of New York, have invented certain new and useful Improvements in Polishing-Wheels, of which the following is a full and true description, reference being had to the accompanying drawings, illustrating one form of my invention.

My invention relates to rotary polishing-wheels for cleaning and polishing the surfaces of metallic articles.

It has for its object to produce a wheel at once more economical, simple, and durable than any heretofore used.

My polishing-wheel consists of a wooden core perforated for the arbor or arbors on which the wheel is secured, with a polishing-body of bristles or fibers secured around the core by a waterproof cement and with wooden clamping-pieces fitted upon the ends of the core and having their grain running in a different direction from the grain of the wooden core.

In Figure 1 accompanying I have shown a plan view (partly broken away) of a polishing-wheel made under my invention, and in Fig. 2 I have shown a sectional view of the same.

A indicates the core of the wheel. It is provided with open ends to receive the ends of the rotating arbor or arbors which hold and drive the wheel.

B indicates the polishing-body, composed of fibers or bristles, with their free ends constituting the circumference of the brush. The inner ends of the fibers or bristles are secured around the core A by means of a compacted waterproof cement C, surrounding the core in the form of a ring. The cement which I prefer to use is composed, essentially, of machine lubricating-oil, fish-glue, rosin, and a drier, (such as chalk,) and I have secured good results when substantially equal quantities of each ingredient are used in the mixture.

I am aware that polishing-wheels have been

made by securing fibers or bristles to a core and attaching them by bending them around wires fitted in holes or recesses in the core. This method tends to shorten the life of the wheel, because the fibers or bristles are strained or broken by bending or doubling them, and they are very apt to break under the severe use to which they are subjected. In addition the boring of hubs and the process of wiring are expensive.

Polishing-wheels are rapidly used up, and it is therefore of the highest importance that such wheels be constructed in an economical manner and that the cement which holds the fibers or bristles shall be well adapted to resist water.

In view of the fact that, say, seventy-five per cent. of the polishing-wheels or buffing-wheels employed are used with water I have found that the waterproof cement described materially increases the useful life of the polishing-wheel.

The core A is cut away at either end, whereby reduced collars D are formed, and a wooden clamping-ring E is fitted upon each of said ends, being held in position by the cement C.

The clamping-rings are fitted upon the core with the grain e of the rings running in a direction different from the grain a of the core.

I am aware that polishing-wheels having a wooden core and wooden clamping-rings have been produced; but I am not aware that the clamping-rings have ever been fitted to the ends of the core in such manner as to have the grain of the clamping-rings run in a direction different from the grain of the core, whereby the cracking or splitting of the core due to the strain given by forcing it on the shaft or by the clamping devices and to the swelling or warping of the core when wet is largely prevented. The use of the waterproof cement is also advantageous in preventing the water from reaching the wooden core.

What I claim is—

1. A polishing-wheel having a wooden core, a radially-extending polishing-body secured to the core, and wooden clamping-rings fitted

upon the ends of the core and surrounding the same, the grain of the clamping-rings running in a direction different from the grain of the core.

5 2. A polishing-wheel comprising a wooden core having reduced ends, a radially-extending polishing-body secured to the core by means of a waterproof cement, wooden clamping-rings fitted upon the reduced ends of the

core, with the grain of the rings running in a direction different from the grain of the core.

In witness whereof I have hereunto signed my name this 14th day of December, 1897.

ALBERT KORTUM.

In presence of—

H. BUCKMEN, Jr.,
CHAS. E. TOMKINS.
